UNITED STATES PATENT OFFICE.

CHARLES PERLEY, OF NEW YORK, N. Y.

CLASP FOR BANK-BILLS, &c.

Specification forming part of Letters Patent No. 43,792, dated August 9, 1864.

To all whom it may concern:

Be it known that I, CHARLES PERLEY, of the city, county, and State of New York, have invented, made, and applied to use a new and useful Improvement in Clasps or Files for Bundles of Bank-Bills, &c.; and I do hereby declare the following to be a full, clear, and exact description of the same, reference being had to the annexed drawings, making part of this specification, wherein—

Figure 1 is a side view of my said clasp. Fig. 2 is an end view of the same, showing the manner in which it is secured together. Fig. 3 is a similar view showing the clasp as open to receive bank-bills or whatever may be desired to be placed therein.

Similar marks of reference denote the same parts.

It has been usual before my invention, when bank-bills or papers are filed or bundled to secure the same by india-rubber bands or by strips of paper wrapped around and secured by sticking a pin through the same. Said india-rubber band soon loses its elasticity and becomes rotten and useless and the pins used to secure bundles of bank-bills deface the same, and there is more or less difficulty in introducing the pins, particularly in warm weather, for said pins soon injure the fingers of those employed in bundling the bills and often tear and deface said bills.

The object of my invention is to provide a cheap and durable metallic clasp or file, and one that will not injure the bills or papers filed therein.

The nature of my said invention consists in a thin strip of spring metal, either steel or brass, bent in a **U** form, the ends of which are secured together by any suitable spring

catch or lock, the one shown and described being preferred.

In the drawings, *a* is a strip of spring metal bent in a **U** form. *b b* are spring-catches bent at right angles to the same and formed as tongues, and *c c* are grooves or cuts to receive said tongues when sprung together by the hand. It will be seen that it is only necessary to press the **U**-form clasp together in order that the rounded portions *1 1* of the tongues shall give a sidewise movement to the ends of the spring as the parts come in contact; thereby one tongue slips over the other and enters its groove, springing down into the same and securing the clasp around a bundle of bills or papers entered within the same.

When it is desired to withdraw bills or papers inclosed within said clasp or file, it may be effected by drawing them out without unclasping the same; and in order to unclasp this device, it is simply necessary to spring the clasp edgewise when the parts will disconnect.

Figures to denote the amount of bills contained in said file or any desired lettering may be engraved or otherwise applied to the same.

Having thus described my said invention, what I claim as my invention, and desire to secure by Letters Patent, is—

A metallic spring clasp or file for bank-bills, &c., held together in substantially the manner described and shown.

In witness whereof I have hereunto set my signature this 3d day of May, 1864.

CHARLES PERLEY.
